UNITED STATES PATENT OFFICE.

WILLIAM A. LORENZ, OF BROOKLYN, AND LOUIS K. JOHNSON, OF NEW YORK, N. Y.

MECHANISM FOR CUTTING OFF AND ELEVATING LINES OF QUADRATS.

SPECIFICATION forming part of Letters Patent No. 244,636, dated July 19, 1881.

Application filed May 28, 1881. (Model.)

To all whom it may concern:

Be it known that we, WILLIAM A. LORENZ, of the city of Brooklyn and State of New York, and LOUIS K. JOHNSON, of the city, county and State of New York, have invented a new and useful Improvement in Mechanism for Cutting Off and Elevating Successive Lines of Quadrats from a block of the same, of which the following is a full, true, and exact description, reference being had to the accompanying drawings.

Our invention relates to an apparatus, by means of which a row of quadrats can be readily seized by the operator and inserted in the page.

Heretofore it has been necessary to select by hand, as needed, quadrats from a reservoir in which they indiscriminately lie. By means of our invention one line of quadrats at a time is separated from the block by mechanism, and is placed in such a position as to be readily seized by the composing operator by means of a hand-grab, and placed in the composing-stick.

Our invention is shown in the accompanying drawings, of which there are two sheets, in which Figure 1 represents a general perspective elevation of our invention. Fig. 2 represents a central vertical section of the same. Fig. 3 represents a section of the horizontal galley, showing the elevating-slide; and Fig. 4 represents a vertical plan of the same, partly in section, showing the upper guide-surfaces.

Our apparatus consists, generally, of a horizontal galley or plate, A', which is provided with the two side pieces or guides g' and m', forming a galley for the reception of a block of quadrats, L', which are separated by the machine and brought within the ready reach of the operator. The galley is supported on the pedestal P', preferably in a horizontal position.

Fixed to the end of the galley is the end plate, N'. The block of quadrats in the galley is forced against this end plate N' by means of a follower or pusher, p², which slides by means of two supports on the rod r², around which it can be swung out of the way of the quadrats. The follower p² is drawn forward by means of the weight w' attached to the cord i. Attached to the end of this cord is a button, b², by means of which this cord i may be attached either to the follower p² or to the galley A' by means of the slot b³.

Resting on the galley A', and fixed to the

end plate, N', by means of screws x', is the adjustable plate C². The distance between C² and N' can be altered by means of the thumbscrews w'. By means of this adjustment quadrats of different thicknesses may be employed.

Attached also to the galley A' is the guide-plate K', which is situated in the same vertical plane as C². This guide-plate K' is slotted about its center at e'.

Between the end plate, N', and the guide-plate K' slides the elevating-plate j', provided with a pin, n², which passes through the vertical slot e'. This pin is raised and lowered by means of the link l', which is attached to the treadle T'. The treadle and link are thrown up by means of the spiral spring s', whereby the elevating-plate is also thrown up. The lower edge of the adjustable plate C² is raised high enough above the galley to allow of the passage of the quadrats L' under it.

On the upper part of the end plate, N', is the lip o'. Attached also to the plate N' is the channeled guide-plate C', the two sides of which form a continuation of the end plate, N', and C².

The operation of the machine can now be understood.

When the treadle is elevated, as shown in Fig. 1, the elevating-plate j' intervenes between the end row of quadrats and the end plate, N'. By depressing the treadle T' the plate j' is withdrawn from between the end line of quadrats of the block L' and the end plate, N'. When this occurs the follower p² forces the block of quadrats forward until the end line of quadrats rests against the end plate, N'. Then by allowing the spring to raise the treadle T and link l' and the elevating-plate j' a single line of quadrats is thrown up, as shown in Fig. 2 at L³. This line of quadrats is supported upon the elevating-plate j' and between the end plate, N', provided with its upper lip, o', and guide-plate C², and is presented to the operator in the space between lip o' and the upper edge of the plate C². The operator seizes the line so presented by means of a hand-grab and draws it into the channel C', from which it is readily raised by means of the grab and placed in the desired position in the composing-stick.

In case quadrats of a greater thickness are

used, the plate C² should be adjusted by means of the screws x' to allow of their passage between it and the end plate, N'.

What we claim as our invention, and desire 5 to secure by Letters Patent, is—

1. In an apparatus for dividing a line of quadrats from a block of the same, the end plate, N', provided with the lip o', substantially as and for the purposes described.
- 10 2. In an apparatus for separating a line of quadrats from a block of the same, the combination of an adjustable plate, beneath which the line of quadrats passes, constructed substantially as described, and the end plate of the apparatus provided with a projecting lip.
- 15 3. In an apparatus for elevating a line of type or quadrats, in combination with an end

plate against which the line of type is advanced, a projecting lip serving to arrest the upward movement of the type, and an elevating-slide which is drawn down by a treadle and elevated by a spring, whereby a line of quadrats or type is cut off from a block, and is automatically held in position between the said slide and the lip, whence it may be removed by the operator without the necessity of a continued depression of the treadle, substantially as described. 20 25
